(57) **CLAIM**

The ornamental design for a mounting rack of auxiliary rear-view mirror, as shown and described.

DESCRIPTION

FIG. 1 is a perspective view of a mounting rack of auxiliary rear-view mirror showing my new design;

FIG. 2 is a front view of the design;

FIG. 3 is a rear view of the design;

FIG. 4 is a left side view of the design;

FIG. 5 is a right side view of the design;

FIG. 6 is a top view of the design; and

FIG. 7 is a bottom view of the design; and,

FIG. 8 is a perspective view showing mounting rack of auxiliary rear-view mirror.

The broken line showing of the rear-view mirror assembly is included for the purpose of illustrating environmental structure and forms no part of the claimed design.
